CLAIM

The ornamental design for a rehairing tool for stringed instrument bows, as shown and described.

DESCRIPTION

FIG. 1 is a perspective view of a rehairing tool for stringed instrument bows, showing my design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof with the sliding insert in an extended position and the pivoting arm in an alternate position;

FIG. 9 is a left side elevational view thereof;

FIG. 10 is a front elevational view thereof;

FIG. 11 is a rear elevational view thereof;

FIG. 12 is a top plan view thereof;

FIG. 13 is a bottom plan view thereof; and,

FIG. 14 is a perspective view of the rehairing tool for stringed instrument bows in an exemplary environment.

The dash-dash-dash broken line showing in the Figures illustrates portions of the rehairing tool for stringed instrument bows and forms no part of the claimed design. The dash-dot-dash broken line showing in the Figures illustrates environment and forms no part of the claimed design.
